UNITED STATES PATENT OFFICE.

JOHN WILLIAM CUNNINGHAM, OF DETROIT, MICHIGAN, ASSIGNOR TO CHICAGO PNEUMATIC TOOL CO., OF NEW YORK, N. Y., A CORPORATION OF NEW JERSEY.

POWER HAMMER.

Application filed August 21, 1922. Serial No. 583,118.

To all whom it may concern:

Be it known that I, JOHN WILLIAM CUNNINGHAM, a citizen of the United States, residing at Detroit, in the county of Wayne and State of Michigan, have invented certain new and useful Improvements in Power Hammers, of which the following is a specification.

My invention relates to a power-hammer preferably, though not necessarily, operated by an electric motor as the prime mover and adapted to hammering purposes, such as chipping, drilling or riveting by means of a chisel, drill, rivet set, or the like, to one end of which the striking member of the hammer imparts its blow. A hammer of this general type is disclosed in United States Letters Patent, No. 1,191,948, granted July 25, 1916 to C. B. Coates, and comprises in general a hollow air cylinder directly reciprocated by the electric or other type of motor and a hammering or impact piston, the reciprocatory motion of the cylinder being imparted to the piston through the instrumentality of the air above and below the piston which delivers a blow at each reciprocation upon the inner end of the shank of the tool inserted into the front end of the barrel within which the hollow cylinder is reciprocated, as is well understood in the art. It is customary in this type of hammer, as exemplified in the Coates patent, to provide the air cylinder with a head on either end and equip the piston with a stem which projects through a central bore in one of the cylinder heads. One of the principal objects of my invention is to improve and simplify the construction and operation of this type of hammer and at the same time increase its efficiency and reliability. To this end, I have employed a power operated air cylinder which is closed at but one end and contains the reciprocating piston, possessing considerable weight and adapted to deliver a sharp, snappy and powerful blow on a tool set through the open end of the cylinder, ports in the cylinder and in communication with the barrel being so positioned and proportioned that the piston is reciprocated with the cylinder in a highly efficient and effective manner.

Others features of advantage and utility in my power-hammer will be apparent from the description hereinafter given.

In the drawings, Figure 1 is a central sec-

tional elevation of my power-hammer and Figs. 2 to 7 are like sectional elevations through the barrel and the hollow air cylinder, showing the latter and the piston in the various and successive positions through which they pass during a single cycle of operation of the device.

My hammer is a power-hammer operated preferably directly by a prime mover located in the hammer structure itself and while any suitable motor may be employed as such prime mover, I prefer an electric motor, and will, therefore, describe my invention in connection with such a motor, so located, without intention of limitation thereto.

Referring to the details of construction as shown in Fig. 1, the motor frame or casing 7 which is of suitable size and shape contains a suitable electric motor 8. This motor has an armature shaft 9 mounted in suitable bearings in the casing 8 and formed at its outer end as a pinion 10 which meshes with a gear 11 secured to the crank shaft 12. This crank shaft is mounted in suitable bearings in a gear case 14 secured to the motor casing. The handle 13 is shaped to receive the grip of the hand of the operator and is secured in any suitable manner to the motor casing and the gear casing. This handle contains the electric motor switch indicated generally at 15 and provided with a button 15^a for convenient operation.

The hammer barrel 16, which may be of suitable dimensions, is adapted to be secured at the lower end of the crank case, this barrel in the present instance being screw threaded at its upper end in order to screw into the crank case. The lower end of the barrel is provided with an opening in which by preference is arranged a bushing 17 to secure the shank of the chisel or drill 18.

A connecting rod 19 is provided at one end with suitable bearings to fit the crank pin of the crank shaft 12 and on the other end with a bearing to fit the pin 20 which passes through parallel lugs projecting from the head 23 which is integral with and closes the upper end of the air cylinder 22. The lower end of the cylinder is open and unrestricted and this constitutes one of the important features of my invention, as the elimination of the head, customarily used at this end of the air cylinder, materially simplifies the construction and reduces the

cost of manufacture. The air cylinder is reduced in diameter intermediate its ends to provide exterior annular flanges 22^a at its upper and lower ends and form an annular space or chamber 24 between the inner walls of the barrel and the exterior walls of the cylinder, the flanges 22^a being turned to form a sliding fit in the bore of the barrel. The air cylinder 22 is provided with a port 25, a port 26 and two ports 27 passing through its walls and communicating with the interior of the cylinder and the annular space 24. These ports are preferably arranged in different planes or points axially of the cylinder and while I preferably employ but one port 25, one port 26 and two ports 27, it will be understood that the number of the various ports is immaterial and may be increased, so long as they are properly proportioned. Located within the cylinder 22 is a hammering piston 28 which is preferably heavier than the usual piston heretofore employed in this general type of machine. The piston is provided with a reduced projecting end through which the piston is adapted to impart its blow to the chisel or drill 18.

Describing a cycle of operation and beginning with the parts in their relative positions, shown in Fig. 2, at which time the air cylinder 22 is in its uppermost position, the piston 28 is still moving upward due to the momentum acquired during the upward stroke of the piston and the air in the upper end of the cylinder is being compressed by the upward movement of the piston 28, the upper end of which has passed and closed the port 25. The upward movement of the piston 28 continues until the air trapped by the piston in the upper end of the cylinder 22 is compressed sufficiently to overcome the momentum of the piston. This uppermost extent of movement of the piston is shown in Fig. 3, in which the cylinder 22 has been moved downward a slight extent, the crank shaft 12 having moved approximately 45 degrees past its upper dead center. At this point, the ports 27 are uncovered by the lower end of the piston, so that the annular space 24 and the interior of the cylinder 22 below the piston are thrown into communication with each other and any loss of air from the annular space 24, which may have occurred during the preceding cycle of operation, is restored so that the air pressure therein is the same as the pressure inside of the lower end of the barrel. The piston 28 now starts to move downward with the cylinder 22 and its downward movement is accelerated due to the expansion of the air trapped in the upper end of the cylinder so that it moves at a more rapid rate than does the cylinder. In Fig. 4 the cylinder 22 is beginning to slow down due to the angular position of the

crank shaft 12, but the piston continues at its high rate of speed acquired during the down stroke of the cylinder. In this figure, the upper end of the piston is just about clearing the port 25 which is smaller than the port 26 and is so placed that the volume of air in the cylinder 22 above the piston, when the upper end of the piston is just closing the port 25, is approximately equal to the volume of air in the annular space 24. If it were not for the port 25, the air in the upper end of the cylinder 22 would begin to be rarefied as the piston continues to move downward from the position shown in Fig. 4 and the partial vacuum produced would retard the speed of the piston and destroy or seriously impair the force of its blow on the chisel or drill 18. This port 25, however, throws the annular space 24 into communication with the upper end of the cylinder so that the rarefaction of the air due to the further downward movement of the piston is retarded and when the piston is advanced slightly to the position shown in Fig. 5, the larger port 26 is uncovered by the piston, which puts the upper end of the cylinder and the annular space 24 into free communication with each other, making the retarding effect due to any partial vacuum above the piston practically negligible, and permitting the piston to impart the full power of its blow on the tool 18. Fig. 5 shows the piston at the instant that it strikes the tool, and this occurs just before the cylinder 22 reaches its lower limit of movement. In Fig. 6 the cylinder 22 is shown at the limit of its downward movement and the piston has delivered its blow and rebounded to cover the port 26. During that portion of the upstroke of the cylinder from its position shown in Fig. 6 to the position shown in Fig. 7, the cylinder and piston move substantially in unison with the upper end of the piston just below the port 25. During this movement, the air in the upper end of the cylinder and in the annular space 24 is under practically uniform or equal pressure and the position of the piston is just sufficient to produce a partial vacuum in the upper end of the cylinder and in the annular space 24 enough to overcome the weight of the piston and cause it to be raised with the cylinder. Now, as the cylinder moves from the position shown in Fig. 7 to its uppermost position, shown in Fig. 2, its movement is retarded and finally comes to rest momentarily, but the piston continues its upper movement at a rapid rate due to its momentum until it is stopped by the air trapped and compressed by it in the upper end of the cylinder which happens during the initial downward extent of movement of the cylinder, as shown in Fig. 3. It is understood, of course, that the lower end of the barrel is properly

vented with the atmosphere to permit free escape to the atmosphere of the air from the lower end of the barrel on the down stroke of the cylinder 22 and piston and admission 5 of air to the barrel on the up stroke of the cylinder 22 and piston.

I have shown the hammer held in a vertical position in the drawings and have described the relation of the parts and the directions of movements of the cylinder 22 and piston 28 with the hammer in such position, but it will be obvious that the hammer may be used in any desired position, even in an inverted position, inasmuch as the action 15 of the hammer depends largely on the inertia of the piston.

I claim:

1. In a power hammer, the combination of a barrel, a power operated hollow cylinder 20 arranged to be reciprocated in said barrel, said cylinder having an unrestricted open end, a piston freely movable in said cylinder, and means whereby the reciprocation of said cylinder imparts movement to said piston 25 to deliver blows upon a working tool through the open end of said cylinder.

2. In a power hammer, the combination of a barrel, a power operated hollow cylinder arranged to be reciprocated in said barrel, 30 said cylinder having an unrestricted open end, a piston freely movable in said cylinder, and means whereby the reciprocation of said cylinder imparts movement to said piston to deliver blows upon a working tool 35 through the open end of said cylinder, said means including an air chamber alternately put in communication with the closed portion of said cylinder above said piston and the open portion of said cylinder below 40 said piston.

3. In a power hammer, the combination of a barrel, a power operated hollow cylinder 45 therein reduced in diameter intermediate its ends to form an annular space between it and the inner walls of the barrel and having its lower end open, a piston freely movable in said cylinder and adapted to have movement imparted thereto by said cylinder, and ports through the wall of said cylinder 50 controlled by said piston whereby said space is alternately placed in communication with the closed portion of said cylinder above said piston and the open portion of said cylinder below said piston.

55 4. In a power hammer, the combination of a barrel, a power operated hollow cylinder therein reduced in diameter intermediate its ends to form an annular space between it and the inner walls of the barrel and having 60 its lower end open, a piston freely movable in said cylinder and adapted to have movement imparted thereto by said cylinder, and means for progressively establishing communication in greater degree between 65 said space and the upper or closed end of

said cylinder above said piston on the working stroke of the latter.

5. In a power hammer, the combination of a barrel, a power operated hollow cylinder therein reduced in diameter intermediate its 70 ends to form an annular space between it and the inner walls of the barrel and having its lower end open, a piston freely movable in said cylinder and adapted to have movement imparted thereto by said cylinder, and 75 ports in the wall of said cylinder successively uncovered by said piston on its working stroke for progressively establishing communication between said space and the upper or closed end of said cylinder above said 80 piston.

6. In a power hammer, the combination of a barrel, a power operated hollow cylinder therein reduced in diameter intermediate 85 its ends to form an annular space between it and the inner walls of the barrel and having its lower end open, a piston freely movable in said cylinder and adapted to have movement imparted thereto by said cylinder, and ports differential in size in the wall of 90 said cylinder successively uncovered by said piston on its working stroke for progressively establishing communication between said space and the upper or closed end of 95 said cylinder above said piston.

7. In a power hammer, the combination of a barrel, a power operated hollow cylinder arranged to be reciprocated in said barrel, 100 said cylinder having an unrestricted open end, a piston freely movable in said cylinder, and adapted to be reciprocated in response to the movements of said cylinder, and an air chamber arranged to be progressively placed in communication with the closed end of said cylinder by said piston on its working stroke to permit the latter to deliver a forceful blow upon the working tool 105 through the open end of said cylinder.

8. In a power hammer, the combination of a barrel, a power operated hollow cylinder having one end closed and the other open and also having two ports at different points intermediate its length and in communication with the interior of the closed end of the cylinder, means affording communication between the ports, and a piston movable in said cylinder, the ports being so positioned that the piston closes one on its rearward stroke and causes a partial vacuum effecting rearward movement of the piston 110 with the cylinder and the piston opens both ports on its forward stroke to permit the piston to deliver its full blow on the working tool.

9. In a power hammer, the combination of a barrel, a power operated hollow cylinder having one end closed and the other open, 115 reduced in diameter intermediate its ends to form an annular space between it and the inner walls of the barrel, and also having 120

two ports at different points intermediate its length and in communication with the interior of the closed end of the cylinder and said annular space, and a piston movable in 5 said cylinder, the ports being so positioned that the piston closes one on its rearward stroke and causes a partial vacuum effecting rearward movement of the piston with the cylinder and the piston opens both ports on 10 its forward stroke to permit the piston to deliver its full blow on the working tool.

10. In a power-hammer, the combination of a barrel, a power operated hollow cylinder having one end closed and the other 15 open and also having two ports at different points intermediate its length and in communication with the interior of the closed end of the cylinder, means affording communication between the ports, and a piston movable in said cylinder, the ports being so positioned that the piston closes but one port during part of its rearward stroke and causes a partial vacuum effecting rearward movement of the piston with the cylinder 20 and finally closes both ports near the end of such movement so that the trapped air serves as a cushion for the piston, and the piston opens both ports on its forward stroke to permit the piston to deliver its 25 full blow on the working tool.

11. In a power-hammer, the combination of a barrel, a power operated hollow cylinder having one end closed and the other open and also having two ports at different 35 points intermediate its length and in communication with the interior of the closed end of the cylinder, means affording communication between the ports, and a piston movable in said cylinder, the ports being so positioned that the piston closes one on its rearward stroke and causes a partial vacuum effecting rearward movement of the piston with the cylinder and the piston opens both 40 ports on its forward stroke to permit the piston to deliver its full blow on the working tool, and said cylinder also having a port in communication with the open end of said cylinder and with the aforesaid ports through said means and opened by said piston 45 during its rearward stroke.

12. In a power-hammer, the combination of a barrel, a power operated hollow cylinder having one end closed and the other open, means affording an annular space 55 between the cylinder and the inner walls of the barrel, said cylinder also having two ports at different points intermediate its length and in communication with the interior of the closed end of the cylinder and said annular space, the volume of the closed 60 end of the cylinder above the plane through the upper port being substantially equal to the volume of said annular space, and a piston movable in said cylinder, the ports 65 being so positioned that the piston closes

only the lower one during the major portion of its rearward movement and causes a partial vacuum effecting rearward movement of the piston with the cylinder, and the piston opens both ports on its forward 70 stroke.

13. In a power-hammer, the combination of a barrel, a power operated hollow cylinder having one end closed and the other open, means affording an annular space between the cylinder and the inner walls of the barrel, said cylinder also having two ports at different points intermediate its length and in communication with the interior of the closed end of the cylinder and said annular space, the volume of the closed 75 end of the cylinder above the plane through the upper port being substantially equal to the volume of said annular space, and a piston movable in said cylinder, the ports being so positioned that the piston closes only the lower one during the major portion of its rearward movement and causes a partial vacuum effecting rearward movement of the piston with the cylinder, and the piston opens both ports on its forward stroke, said cylinder also having a port in communication with its open end and said annular space and uncovered by said piston near the end of its rearward stroke.

14. In a power-hammer, the combination of a barrel, a power operated hollow cylinder having one end closed and the other open, reduced in diameter intermediate its ends to form an annular space between it and the inner walls of the barrel and also having two ports at different points intermediate its length and in communication with the interior of the closed end, the volume of the closed end above the plane through the upper port being substantially equal to the volume of the annular space, and a piston movable in said cylinder, the ports being so positioned that the piston closes the lower one during the major portion of its rearward movement and causes a partial vacuum effecting rearward movement of the piston, closes the upper port near the end of such movement so the trapped air serves as a cushion and opens both ports on its forward stroke.

15. In a power-hammer, the combination of a barrel, a power operated hollow cylinder slidably fitting therein, said cylinder having ports at three different points intermediate its length and communicating with the interior of the cylinder, means affording communication between the ports at the three points, and a piston movable in the cylinder and controlling the opening and closing of said ports.

16. In a power-hammer, the combination of a barrel, a power operated hollow cylinder slidably fitting therein, having one end open and also having ports at three dif-

- ferent points intermediate its length and communicating with the interior of the cylinder, means affording communication between the ports, and a piston movable in 5 said cylinder and adapted to deliver its blow on the working tool through the open end of the cylinder.
17. In a power-hammer, the combination of a barrel, a power operated hollow cylinder therein having its lower end open, reduced in diameter intermediate its ends to form an annular space between it and the inner walls of the barrel and having ports at three different points intermediate its length and communicating with its interior 15 and said annular space, and a piston movable in said cylinder and adapted to open and close said ports and to deliver its blow on the working tool through the open end of the cylinder.

JOHN WILLIAM CUNNINGHAM.
